Emery, Booth, Jamney & Varney.

UNITED STATES PATENT OFFICE.

MICHELE DEL CIOPO, OF NEW YORK, N. Y.

IRONING-BOARD.

1,271,674.

Specification of Letters Patent.

Patented July 9, 1918.

Application filed February 28, 1918. Serial No. 219,559.

To all whom it may concern:

Be it known that I, MICHELE DEL CIOPO, a subject of the King of Italy, and a resident of the borough of Manhattan, in the city, county, and State of New York, have invented an Improvement in Ironing-Boards, of which the following is a specification.

My invention relates to ironing boards. 10 It is the object of the present invention to provide in ironing boards such an arrangement of parts as will render the same simple in construction and convenient in use.

By way of example I have illustrated a 15 preferred embodiment of my invention in the accompanying drawings, wherein:

Figure 1 is a side plan view of such embodiment partly in cross-section;

Fig. 2 is a top plan view of the same with 20 a different auxiliary garment-supporting device substituted for the auxiliary garment-supporting device shown in Fig. 1;

Fig. 3 is a top elevational view of one 25 form of auxiliary garment-supporting device;

Fig. 4 is a similar view of another form of such device.

Referring to the embodiment of my invention herein shown and described by way 30 of example merely, 1 represents the base of the device which may have any desired configuration, but which is preferably of elongated form, as illustrated. Secured to the base 1 are one or more supporting members, 35 comprising preferably a main supporting member, indicated generally by the numeral 2, and an auxiliary supporting member 3. Preferably the main supporting member 2 comprises a supporting sleeve 4 having a 40 reduced portion 5 fitting within an opening 6 in the base 1. There is thus provided a shoulder or abutment 7 which constitutes engaging means between the sleeve 4 and the base 1. Supported on the main supporting member 2 is the main garment-supporting device 8 which may have any desired configuration, but which is preferably, as 45 illustrated, in the form of an elongated board of the shape usual for such devices. 50 In order to properly position parts 1, 4 and 8 in spaced relation, I prefer to employ a retaining member in the form of a bolt 9

having a head 10 attached thereto, as by being made integral therewith, and having its other end screw threaded, as at 11. To 55 provide means for engagement between the garment-supporting device 8 and the retaining member 9, I prefer to provide the lower face of the device 8 with the opening 12 communicating with the groove 13 so 60 that the head 10 of the bolt 9 may be inserted into the opening 12 and slid into the groove 13, whereupon the bolt 9 carried by the device 8 may be passed through the sleeve 4 and its free end engaged by the 65 thumb or wing nut 14 to position the parts in proper relation to each other. In order to permit easy manipulation of the nut 14 on the threaded end 11 of the bolt 9, I prefer to provide the lower face of the base 1 70 with the cut away portion 15 which is so proportioned as to provide an abutment or stop 16 for the nut 14. It will be apparent, since the head 10 of the bolt 9 is substantially circular in form, as illustrated, that 75 while the parts 1, 4, and 8 are held in spaced relation, the garment-supporting device may be rotated so that its ends will project free of the base 1.

In order to more securely position the 80 longer, free end of the device 8, I prefer to use auxiliary supporting means, comprising, in the illustrative embodiment herein shown and described by way of example, the auxiliary supporting member 3 already 85 referred to. This auxiliary supporting member preferably comprises a stem 17 provided with the dowels 18 and 19 at its opposite ends, the dowel 19 fitting into a socket 20 in the base 1 so as to be removably positioned therein, while the dowel 18 fits into a socket 21 in the auxiliary garment-supporting device 22^a, which is therefore detachably and rotatably positioned on the member 3. The parts are so proportioned 90 that with the device 22^a in position on the member 3, the free end of the device 8 will bear against the upper surface of part 22^a so as to be supported thereby when the device 8 is so positioned as to lie over part 95 22^a. The part 22^a is one of a plurality of interchangeable auxiliary garment-supporting devices, the device 22^a (see Figs. 1 and 3) constituting a substantially round board

for facilitating the ironing of puffs, shoulders of garments, and the like, while the device 22^b (see Figs. 2 and 4) is in the form of a substantially oval board suited for the 5 ironing of sleeves, and the like.

The assembling and use of the device will be substantially clear from the foregoing description. After the bolt 9 has been inserted in opening 12 and slid into slot 13 of 10 the device 8, the latter is placed over the base 1 so that the bolt 9 will pass through the bore 23 of the sleeve 4, the outer threaded end 11 of the bolt 9 passing through the opening 5 in which the reduced end 6 of the 15 sleeve 4 is positioned. Application of the nut 14 to the threaded end 11 of the bolt 9 causes the parts to be properly positioned with respect to each other, the device 8 being detachably but rotatably positioned on the 20 sleeve 4. Any one of the auxiliary garment-supporting devices 22^a, 22^b, is now placed upon the removable auxiliary supporting member 3, and the device 8 is so positioned as to bear against the upper face of the 25 auxiliary supporting member. When the auxiliary garment-supporting device is to be used, the device 8 may be rotated so as to be clear of the same, or if desired, said device 8 may be removed. If desired, the 30 auxiliary garment-supporting device then in position on the supporting member 3 may be interchanged for any other suitable auxiliary garment-supporting device.

It is of course to be understood that my 35 invention is not to be limited to the specific embodiments herein shown and described by way of example.

What I claim is:

1. An ironing board comprising a base, 40 a supporting member positioned on said base, a garment-supporting device rotatably positioned on said supporting member, an auxiliary supporting member for one end of said garment-supporting device, and 45 means independent of said first mentioned supporting member for supporting said auxiliary supporting member, said auxiliary supporting member comprising an auxiliary garment-supporting device.

50 2. An ironing board comprising a base provided with an opening therein, a supporting member in the form of a sleeve having a reduced portion adjacent one end thereof fitting within said opening and providing 55 a shoulder portion engaging said base, a garment-supporting device supported by said member, a retaining member passing through said sleeve for holding said base, supporting member and device in spaced relation, and an auxiliary support for one end 60 of said device, said auxiliary support comprising an auxiliary, garment-supporting device.

3. An ironing board comprising a base

provided with an opening therein, a supporting member in the form of a sleeve having a reduced portion adjacent one end thereof fitting within said opening and providing a shoulder portion engaging said base, a garment-supporting device supported by said member, a retaining member passing through said sleeve for holding said base, supporting member and device in spaced relation, and auxiliary supporting means for said device comprising an auxiliary supporting member and an auxiliary garment-supporting device detachably positioned by said auxiliary supporting member. 65 70 75

4. An ironing board comprising a base 80 provided with an opening therein, a supporting member in the form of a sleeve positioned within said opening, a garment-supporting device detachably supported by said member, and a retaining member passing 85 through said sleeve for holding said base, supporting member and device in spaced relation, said device being provided with a slot for engagement with one end of said retaining member, and said base being provided with a cut-away portion providing an 90 abutment for engagement with the other end of said retaining member. 95

5. An ironing board comprising a base 100 provided with an opening therein, a supporting member in the form of a sleeve having a reduced portion adjacent one end thereof fitting within said opening and providing a shoulder portion engaging said base, a garment-supporting device detachably supported by said member, a retaining member passing through said sleeve for holding said base, supporting member, and device in spaced relation, said device being provided with a slot for engagement with one end of said retaining member, and said base being provided with a cut-away portion providing an abutment for engagement with the other end of the said retaining member, and auxiliary supporting means 105 for said device comprising an auxiliary supporting member and an auxiliary garment-supporting device positioned by said auxiliary supporting member. 110

6. An ironing board comprising a base 115 provided with an opening therein, a supporting member in the form of a sleeve having a reduced portion adjacent one end thereof fitting within said opening and providing a shoulder portion engaging said base, a garment-supporting device supported by said member, a retaining member passing through said sleeve for holding said base, supporting member and device in spaced relation, and auxiliary supporting means for said device comprising an auxiliary supporting member and an auxiliary 120 interchangeable garment-supporting 125 device.

device positioned by said auxiliary supporting member.

7. An ironing board comprising, in combination, a base, a garment supporting device, means interposed between said base and said garment-supporting device for rotatably securing said garment-supporting device to said base, an auxiliary supporting member for one end of said garment-

supporting device, and means independent of 10 said first mentioned means for rotatably supporting said auxiliary supporting member, said auxiliary member comprising an auxiliary garment-supporting device.

In testimony whereof, I have signed my 15 name to this specification this 27th day of February, 1918.

MICHELE DEL CIOOPPO.
